UNITED STATES PATENT OFFICE.

CHARLES LEACH, OF KANSAS CITY, KANSAS.

SASH-FASTENER.

No. 847,345.

Specification of Letters Patent. Patented March 19, 1907.

Application filed September 24, 1906. Serial No. 335,860.

To all whom it may concern:

Be it known that I, CHARLES LEACH, a citizen of the United States, residing at Kansas City, in the county of Wyandotte and State of Kansas, have invented certain new and useful Improvements in Sash-Fasteners, of which the following is a specification.

My invention relates to improvements in sash-fasteners, and relates more particularly to that style adapted to be secured to the top of the lower window-sash and bear against the adjacent side of the window-case in such a manner as to prevent the sash from being raised until the fastener is disengaged from the case.

The invention consists in the novel construction, arrangement, and combination of parts hereinafter described, pointed out in the claims, and illustrated in the accompanying drawing, in which—

Figure 1 represents a side elevation of the fastener in an operative position. Fig. 2 represents a plan view of the fastener. Fig. 3 is a vertical central section taken on line III III of Fig. 2.

In said drawing, 1 designates the window-case, and 2 and 3 the upper and lower window-sashes, respectively, slidably arranged in the case in the customary manner.

4 designates a base-plate secured to the top of the lower sash adjacent to one side of the case. Said plate is provided with a pair of centrally-disposed ears 5 and a rearwardly-disposed lip 6.

7 designates a wedge adjustably mounted upon the base-plate and provided with a stem 8, extending loosely through the lip and provided at its rear terminal with a knob 9, whereby the wedge may be slid backward or forward.

10 designates an expansion-spring embracing the stem and interposed between the lip and the rear terminal of the wedge for the purpose of normally pressing the latter forward.

11 designates a cam pivotally mounted upon a pin 12, secured to the ears, said cam being provided with an enlarged segmental head 13, adapted to engage the adjacent side of the case. The rear portion 14 of the cam is eccentric to pin 12, so that it will be impos-

sible to disengage head 13 from the case until the wedge is withdrawn from contact with said eccentric portion. Wedge 7 fits snugly between ears 5, which, in conjunction with lip 6 and stem 8, act as guides for the wedge and prevent it from shifting laterally beneath the rear portion of the cam. By forcing the wedge forward into contact with rear portion 14 through the instrumentality of spring 10 all wear on said terminal, the wedge, and the pin will be taken up. Hence the cam will be reliably held in contact with the case. This form of adjustment also permits the cam to accommodate itself to any irregularities which may exist in the surface of the case.

The rear terminal of the cam is beveled, as shown at 15, so that when it is desired to hold head 13 out of engagement with the case preparatory to raising the sash the cam is raised to the position indicated by dotted lines, Fig. 1, where it is retained by the wedge engaging the beveled terminal 15.

From the above description it is apparent that I have produced a sash-fastener which is simple in construction, may be manufactured at small cost, and is well adapted for the purpose intended.

Having thus described my invention, what I claim, and desire to secure by Letters Patent, is—

1. A sash-fastener consisting of a base-plate, a cam pivotally secured to said base-plate, provided with a beveled rear terminal and an eccentric rear portion, and a wedge adapted to engage either the beveled end or the eccentric portion and lock the cam in an inoperative or operative position respectively.

2. A sash-fastener consisting of a base-plate, a cam pivotally secured to said base-plate provided with a beveled rear terminal and an eccentric rear portion, and a spring-actuated wedge adapted to engage either the beveled end or the eccentric portion, for the purpose described.

In testimony whereof I affix my signature in the presence of two witnesses.

CHARLES LEACH
